(57) **CLAIM**

The ornamental design for pliers, as shown and described.

DESCRIPTION

FIG. 1 is a front elevational view of a pliers.

FIG. 2 is a rear elevational view of the pliers of FIG. 1.

FIG. 3 is a right elevational view of the pliers of FIG. 1.

FIG. 4 is a left elevational view of the pliers of FIG. 1.

FIG. 5 is a top plane view of the pliers of FIG. 1.

FIG. 6 is a bottom plane view of the pliers of FIG. 1; and, FIG. 7 is a perspective view of the pliers of FIG. 1.

The broken lines showing the handle grips of the pliers are not claimed as part of the inventive design.
